UNITED STATES PATENT OFFICE.

FREDERICK WILLSON AND HARRY F. SHINDEL, OF READING, PENNSYLVANIA,
ASSIGNORS TO T. A. WILLSON & CO., INC., OF READING, PENNSYLVANIA, A COR-
PORATION OF PENNSYLVANIA.

GOGGLES.

1,401,572.

Specification of Letters Patent. Patented Dec. 27, 1921.

Application filed August 23, 1919. Serial No. 319,307.

To all whom it may concern:

Be it known that we, FREDERICK WILLSON and HARRY F. SHINDEL, both citizens of the United States, residing at Reading, in the county of Berks and State of Pennsylvania, have invented certain new and useful Improvements in Goggles, of which the following is a specification.

This invention relates to eye protectors; and it consists in the improved construction hereinafter set forth in connection with the accompanying drawing, and the novel features of which are fully described, and specifically defined in the claims.

Figure 1 is an inner face view of a complete eye protector embodying the several features of the invention in preferred form; one of the pivoted eye shields being represented in outwardly-swung operative position, and the other one, together with the pivoted temple indicated, being shown in folded position.

Fig. 2 is a corresponding top-edge view; the left hand clamping clip and its attached head connection being disconnected and shown separately in Fig. 3.

Fig. 4 is an outside-edge view of the split lens clamping framing, as it appears preliminary to inserting the lens; the latter being shown separately in Fig. 5 in connection with an edge-reinforcing ring. The eye shield is indicated in raised position.

Fig. 6 is a similar view to Fig. 4, but showing the framing preliminarily closed upon the inserted lens, and so held by the fully swung eye shield.

Fig. 7 shows the separately formed framing end-pieces.

Fig. 8 is an enlarged view of a portion of the lens framing, in connection with a showing of the clamping clip as about to be engaged with the framing end pieces; Fig. 9 being a similar view showing the fully engaged clip, in vertical section.

Figs. 10 and 11 are vertical views of the clip and of the nose-bridge end portion respectively.

Each lens framing, as shown, is formed of folded sheet material, with a lens-edge engaging portion 10, and a circular eye cup or flange extension 11; and is provided with end-piece members 12, 12 adapted to be clamped together for securing the inserted

lens 13. The eye shield 15, pivoted to the lens framing extension 11 at 16, 16, has its curved base portion 17 formed with a circular groove 18 which is adapted to engage the top-edge portion of the framing extension 11 when the shield is swung outward to its operative position; the shield, when thus engaged, holding the abutting end piece members 12, 12 together so as to retain the previously inserted lens and permit the easy application of the spring-clip 20 to said members. This clip is attached to the usual temple or head band connection 21 and is adapted to clampingly engage the end piece members 12, 12 in a manner similar to that shown in Willson Patent No. 1,323,431 of Dec. 2, 1919, but with improved effect as hereinafter fully described.

The end-piece members 12, 12, as shown in Fig. 7, are separately formed, with flange portions 22 for rigidly securing them to the abutting ends of the split lens framing; and they consist of abuttingly arranged plates, the lower portions of which are formed with clip-fulcruming offsets 25 on their inner edges, and the upper portions with tit-engaging recesses 26 to provide frictional engagement with the fully engaged clip. The latter, as shown particularly in Figs. 8, 9, and 10, is formed from a folded sheet metal blank; its spaced-apart walls providing a flared opening 27 between them for the easy passage of the abutted end piece members 12, 12, and being connected by a bottom cross-bar 28 which is adapted to engage the fulcruming offset 25 of said members. Extending portions 30, 30 of the clip walls form a temple bar connecting jaw, and inwardly projected tits 31 of the clip walls are arranged to frictionally engage the recesses 26 of the end-piece members after the fulcrumed clip has been forced into fully engaged position upon said members.

The circular extension 11 of the framing, which forms a shallow eye cup portion and serves, as already described, for connection of the pivoted eye shield, and for clampingly engaging the latter when in outswung position, is specially shaped in that portion thereof which is positioned adjacent the nose of the wearer so as to provide a proper nose contact; said portion being flattened, and its edge inwardly turned, to conform it approxi-

mately with the spreading sides and rounded base of the nose. The nose bridge connection of the framings consists of a shaped bridge bar, having T-shaped ends formed by separate plates 35; the raised intermediate portion of each of said plates being shaped to firmly seat the turned end of the bridge bar, which is rigidly secured thereto, and the ends of the plates being shaped to the curvature 10 of the framing extension 11 and suitably fastened to the latter so as to provide any determined spread of the lens framings.

In assembling the parts, or in removing and replacing the lens, the pivoted shield operates in connection with the detachable spring clip to greatly facilitate the clamping operation. The shield itself is adapted to hold the split framing together, upon the readily inserted lens; and it enables the 15 spring clip, which completes the clamping, and firmly secures the temple or head securing means, to be easily applied or removed; while the improved clip construction provides a convenient fulcrum upon which the 20 device is swung with proper leverage for securing the final frictional engagement. The special shaping of the eye cup framing extension to which the eye shield is pivoted, adapts the latter to serve as a preliminary 25 lens-clamping means and at the same time provides a symmetrical nose-contact and for the improved nose-bridge attachment.

What we claim is:-

1. In an eye protector, a lens-clamping framing having opposed end-piece members and an eye-cup extension, a detachably engaged spring-clip band for the abutted members, and a pivoted eye shield adapted to hold said members together without interfering 35 with the operation of said band.
2. In an eye protector, a lens-clamping framing having opposed end-piece members with clip-fulcruming offset, and a detach-

ably engage spring-clip encircling said members and having an offset-engaging crossbar. 45

3. In an eye protector, a lens-clamping framing having opposed end-piece members with clip-fulcruming offset, and a detachably engaged spring-clip encircling said members and having an offset-engaging crossbar adjacent one end of its opening and a friction catch 50 adjacent the other end thereof.

4. In an eye protector, a lens-clamping framing having opposed end-piece members with clip-fulcrumed offset, and a detachably 55 engaged spring-clip encircling said members and having an offset-engaging crossbar adjacent one end of its opening, a friction catch adjacent the other end thereof, and a temple-connecting jaw. 60

5. In an eye protector, a lens-clamping framing having opposed end-piece members with clip-fulcrumed offset, and a detachably engaged spring-clip encircling said members and having an offset-engaging crossbar and 65 a temple-connecting jaw adjacent one end of its opening, and a friction catch adjacent the other end thereof.

6. In an eye protector, a lens-clamping framing having opposed end-piece members 70 with clip-fulcruming offset, and a detachably engaged spring-clip encircling said members and having an offset-engaging crossbar; the encircling portion of said clip having a flared opening for passage of the 75 engaged end-piece members.

7. In an eye protector, a pair of lens framings each having an eye-cup extension, and a nose bridge bar having rigid T-shaped curved end portions extending circumferentially of the respective cups and rigidly secured to the latter. 80

In testimony whereof we affix our signatures.

FREDERICK WILLSON.
HARRY F. SHINDEL.
